UNITED STATES PATENT OFFICE.

JAMES M. PEERSON, OF HUNTSVILLE, ALABAMA.

DOUBLE-BOX COTTON PRESS.

Application filed February 10, 1921. Serial No. 443,940.

To all whom it may concern:

Be it known that I, JAMES M. PEERSON, a citizen of the United States of America, residing at Huntsville, in the county of 5 Madison and State of Alabama, have invented certain new and useful Improvements in Double-Box Cotton Presses, of which the following is a specification.

My invention relates more particularly to 10 a cotton press of the double box type wherein I provide mechanism to co-operate with one box for the purpose of tramping and preliminarily compressing the cotton therein, and a hydraulic ram co-operating with 15 the other box to complete the compression of the bale.

Heretofore the tramping mechanism and the source of hydraulic pressure have been independent and it is a prime object of my 20 invention to utilize the power as applied to the operation of the trumper to generate the hydraulic pressure for the operation of the ram.

A further object of my invention is to 25 utilize the column about which the box revolves as a cylinder for a piston which is operated with the trumper to generate there- 30 in hydraulic pressure for the hydraulic ram. This piston forms an ideal guide for the trumper platen.

A further object of my invention is to 35 simplify and perfect a drive for the trumper which will function most efficiently in connection with the operation of the hydraulic pump in the press column.

A further object is to provide a drive for the trumper of such character that it will 40 permit the trumper platen to drop by gravity after completing its up stroke, the drive 45 being adapted to resume its thrust on the trumper as soon as the latter comes to rest on the cotton or other material. The purpose of this arrangement is to expedite the 50 operation of the trumper by permitting it to drop by gravity onto the material in the press and I desire to claim the novel features of the trumper as applied to feeding under pressure any material into a press, mill, or receiver of any type.

55 My invention further comprises the novel details of construction and arrangements of parts, which in their preferred embodiment only are illustrated in the accompany-

ing drawings which form a part of this specification, and in which:

Fig. 1 is a side elevation of a double box cotton press embodying my present invention.

Fig. 2 is a top plan view of Fig. 1.

Fig. 3 is an enlarged detail sectional view taken on the line 3-3 of Fig. 1.

Fig. 4 is a detail view of a modified type of cam operating ratchet wheel.

Similar reference numerals refer to similar parts throughout the drawings.

In the embodiment of my invention illustrated, 1 represents the bottom sills of a double box cotton press and on the center of these is mounted by means of a bolt 2 a cylindrical base 3 into which the press column 4 is

screwed. The bolt 2 passes up between the sills 1 and screws into the bottom of the cylindrical base 3. It carries a nut and washer 5 on its lower end by means of which the said base 3 is rigidly bolted in position on the sills 1. The column 4 at its upper

end carries a collar 6 which engages the underface of the top beams 7. The column 4 projects between the top beams 7 and its upper end is threaded to receive a gland 8 which screws down thereon against a heavy washer 9 engaging the top face of the beams 7. The sills 1 and beams 7 at each side are

connected and braced together by bolts 10 and the frame is thus rigidly organized for the reception of the double box press 11 which is of any standard type, having suitable cross battens 12 on its opposite sides, the upper of which carry a centering plate 13 which turns with a snug fit about the column 4, and the lower of which battens carry a bearing sleeve 14 which rests and turns on the top of the column support 3 about the column 4 as an axis. Below the left hand

press box I show the usual type of hydraulic ram 15, the plunger 16 of which works in a cylinder 17 rigidly attached at its upper end to the base sills 1. The ram is adapted to compress the bale between it and a presser head 18 attached to the underface of the top beams 7. The right hand press box is

in alignment with the trumper platen 19 which carries a center operating bar or stem 20. The platen operating mechanism comprises a pair of spaced overhead beams 21

which pass on either side of the platen bar 20 and are pivotally connected thereto by a cross bolt 22 working in a transverse slot 26. These beams at their other end are 5 pivotally connected by a pin 23 to the upper end of a rocking standard 24 which at its base is interposed between the beams 7 and pivotally connected thereto by a bolt 25. These beams 21 carry near the centers of 10 their upper edges a pair of bearings 27 in which is mounted a cross pin 28 that carries a roller or sleeve 29 disposed crosswise of and above the beams. This roller is adapted to be engaged by an overhead cam having 15 a substantially spiral curved working face 30 and a substantially radial idle face 31 connecting the outer and inner ends of the curved working face. The cam is keyed on a shaft 32 turning in bearings 33 which 20 are underhung from two overhead beams 34 supported by uprights 35 and forming a rigid superstructure above the press. I also mount fast on the shaft 32 a ratchet wheel 36, the wheel and cam being both disposed 25 between the beams 34. The ratchet wheel 36 is adapted to be operated by a pair of pawls 37 and 38 pivotally connected to opposite ends of a vertical rocker bar 39 journaled in bearings 40 on the beams 34 and having its lower 30 end connected by a link 41 with a crank 42 on the main drive shaft 43 which turns in bearings 44 on top of one of the beams 34, this shaft being driven by a pulley 45 from any suitable source of power. The trumper 35 operating beams 21 carry a cross pin 46 carrying a pawl 47 which is held from falling over to the left by a stop pin 48 and which is adapted when raised with the up stroke of the beams 21 to engage the ratchet wheel, as 40 shown by the dotted lines in Fig. 1. The cam at the outer end of its radial face 31 is provided on each side with a pair of rollers 49 which are adapted to engage the inclined under faces of the trip bars or plates 50 45 which are rigidly mounted on the inside faces of the beams 21 in position to straddle the cam and to be engaged by the rollers 49 moving clockwise so that the latter will lift the beams 21 to their raised or dotted position (Fig. 1.) When the rollers 49 release the plates 50 the platen and beams 21 are free to drop by gravity until arrested by the cotton, and when this occurs, the pawl 47 by its engagement with the ratchet wheel 36 55 will rotate the latter and with it the cam 30 through an arc proportionate to the platen's free fall. This rapid drop of the platen will not be opposed by the engagement of the pawl 47 with the ratchet wheel 36 as the latter is free to be turned forward idly by the pawl 47 during the gravity drop of the platen, and, as soon as the material in the 60 press box stops the gravitating movement of the platen, the pawls 37 and 38 will at once 65 resume their drive on the ratchet wheel, thus

turning the cam and forcing the platen downwardly until its full downward or power stroke has been completed.

The hydraulic pump mechanism, which is operated by and forms the guide for the 70 trumper, comprises a pump piston 51 on the plunger rod 52 that is reciprocable in the column 4 as a pump cylinder, its upper end passing through the gland 8 and being received between and pivotally connected to 75 the beams 21 by a pin 53. The reciprocation of the platen will thus involve a reciprocation of the pump plunger and this in turn will generate the necessary hydraulic power for operating the ram in the following manner. Upon the up or idle stroke of the plunger fluid will be drawn into the base of the column through a pipe 54 leading from a storage tank 55 to which is also connected the pipe 56 forming the exhaust for 80 the ram cylinder. A check valve 57 in the intake pipe 54 will open towards the pump to admit fluid but which will close against pressure from the pump. A pipe 58 having a check valve 59, which will open responsive 85 to pressure in the pump, leads to a four-way valve 60 having one branch 61 connected to a compression tank 62, there being a globe valve 63 in the branch 61. Another branch 64 from the four-way valve connects to the 90 exhaust pipe 56, and the third branch 65 serves as the fluid pressure supply pipe for the ram. I provide valves 66 and 67 in the pipes 54 and 56, respectively, and below these valves I provide a regulating valve 100 68 in the pipe 54 having a spring-pressed stem 69 forming a plunger which moves outwardly responsive to a predetermined pressure in a casing 70 interposed in the exhaust line 56 below the valve 67. This regulating 105 valve 58 and the casing 70 are rigidly mounted on a bracket or support 71 which will hold them in operating relation.

If it is desired to operate the trumper only, the four-way valve 60 is set to open 110 pipe 65 through the branch 64 to the exhaust pipe 56 and thus the fluid will circulate idly between the pump and storage tank. If it is desired to cut off the circulation entirely, it is only necessary to close the valve 66 115 which cuts off any return circulation between the tank 55 and the pump, it being noted that the piston does not have a tight enough fit in the column to have its operation substantially interfered with by a vacuum created below it on its up stroke. When it is desired to bring the pump into operation the four-way valve 60 is turned to connect the pipes 58 and 65 and I open valve 66 and thereafter, the tramping of a bale will proceed contemporaneously with the operation of the hydraulic pump which will deliver the requisite fluid pressure to the ram to press the previously tramped bale. The amount of pumping duty can be controlled by the 120 125 130

action of the automatic valve 68 which can center being engaged by the operating pawls as the platen approaches the end of the up stroke of the piston will draw into its power stroke.

- 5 It will be noted that after the roller on the beams 21 has reached the base of the radial cam wall 31 it will be engaged by the inner end of the curved working face which is plotted on an abrupt curve to effect a 10 rapid initial movement of the platen and pump. As soon as the outer gradually curved face of the cam engages the roller the movement thereafter imparted to the platen and pump is slow and of great power. 15 By this arrangement I obtain from the cam a relatively quick return of the platen to its raised position, a rapid down drive through the major portion of the down stroke of the platen and pump when the piston does not 20 drop by gravity, and a slow powerful drive completing the down stroke of the platen and pump. When the platen drops by gravity the initial portion of the cam's stroke becomes idle and practically instantaneous. 25 The peculiar construction of the cam's working face nearest its center which first engages the platen operating beams 21 is so designed as to afford a very high ratio of leverage because of the short radius from 30 the cam center as compared with the radius of the ratchet wheel, and this high leverage is accompanied by a rapid thrust imparted for the major portion of the stroke to the pump plunger. It is to be noted that the 35 completion of the pumping stroke is derived from the very gradually inclined face of the cam which produces a slow and powerful movement of the plunger. This slow powerful movement is used to do the high pressure pumping, when only a small amount 40 of fluid should be admitted for the pump on its up stroke so that it is only the final part of the down stroke of the plunger which functions to pump under heavy load conditions. 45

Where it is desired to stop the operation of the apparatus, it is only necessary to move upwardly into its full line position (Fig. 1), a trip bar 72 which, as the beams 21 50 are raised, will engage the pawls 36 and 37 and disengage them from the ratchet wheel just before the rollers 49 release the trip plates 50 on the beams 21. This will hold all parts of the press in raised position. 55 The trip bar when in its raised position engages a permanent stop pin 73 and can be held rigidly in this position by a detachable stop pin 74 which must be removed to drop the trip bar to dotted line position. If it be 60 desired to increase the power derived from the ratchet wheel while the platen is approaching the limit of its power stroke, this can be accomplished by an eccentric mounting of the ratchet wheel 75, as seen in Fig. 65 4, the teeth most remote from the wheel

The upper end of the platen bar 20 is guided between rolls 76 mounted in bearings 77 on top of the overhead beams 34. My trumper mechanism is capable of adaptation to various types of presses and to pressure feeding of any suitable material into a hopper or container, or into a press 75 of any character.

This invention is not intended to be restricted in scope to the specific embodiments shown, but contemplates such modifications as come within the spirit and scope of the 80 claims.

Having thus described my invention, what I claim as new and desire to secure by Letters Patent, is:—

1. The combination with a receptacle, of a platen reciprocable thereinto, a rocking beam pivotally connected at one end to the platen and at the other end to a support, means to guide the platen, and cam driving means to raise and lower said rocking beam 90 to reciprocate the platen.

2. In combination, a receptacle, a platen reciprocable thereinto, guides for the platen, an operating mechanism for the platen comprising a reciprocable member connected to the platen, and power driven means adapted to lift, release and follow the member down to complete the power stroke of the platen.

3. In combination, a receptacle for material to be compressed, a platen reciprocable thereinto, an operating mechanism for the platen comprising means to lift and release the platen for a gravity drop, and means to engage and positively drive the 105 platen for the remainder of its stroke downwardly.

4. In combination, a receptacle for material to be compressed, a platen reciprocable thereinto, an operating mechanism for the platen comprising means to lift and release the platen for a gravity drop, and means to drive the platen positively for the remainder of its stroke downwardly, said means comprising a driving cam.

5. In combination, a receptacle for material to be compressed, a platen reciprocable thereinto, an operating mechanism for the platen comprising means to lift and release the platen for a gravity drop, and means to follow up and positively drive the platen the remainder of its stroke downwardly, said means comprising a driving cam, and a pawl and ratchet drive for the cam.

6. In combination, a receptacle for material to be compressed, a platen reciprocable thereinto, an operating mechanism for the platen comprising means to lift and release the platen for a gravity drop, and means to engage and positively drive the platen the 130

remainder of its stroke downwardly, said means comprising a driving cam, and a pawl and ratchet drive for the cam, the cam having a curved working face with a sharp 5 slope at the commencement of its working face and a very gradual slope throughout the remainder of its working face, said remainder of the working face being called on to impart the final downward movement 10 to the platen.

7. The combination with a press box, of a reciprocable platen therefor having guides and a reciprocating mechanism comprising a trip mechanism to lift and release the 15 platen, and a pawl and ratchet driven cam for driving the platen the remainder of its down stroke.

8. The combination with a press box, of a platen reciprocable thereinto, guides for 20 the platen, a pivoted driving arm for the platen, a power driven cam adapted to engage and depress said arm, a trip on the arm, and a roller movable with the cam to engage the trip and lift the arm and platen 25 to elevated position before releasing them.

9. The combination with a press box, of a platen reciprocable thereinto, guides for the platen, a pivoted driving arm for the platen, a power driven cam adapted to engage 30 and depress said arm, a trip on the arm, a roller movable with the cam to engage the trip and lift the arm and platen to elevated position before releasing them, and a pawl and ratchet drive for the cam.

35 10. The combination with a press box, of a platen reciprocable thereinto, guides for the platen, a pivoted driving arm for the platen, a power driven cam adapted to engage and depress said arm, a trip on the 40 arm, a roller movable with the cam to engage the trip and lift the arm and platen to elevated position before releasing them, a pawl and ratchet drive for the cam, and a pawl on said arm adapted in raised position to engage the ratchet wheel and throughout the platen's gravity drop to advance it independently of its driving pawls.

11. In combination, a rocking pawl arm, 50 power means adapted continuously to oscillate said arm, pawls connected to the arm on opposite sides of its axis, a ratchet wheel driven by the pawls, a cam driven by the ratchet wheel, a pivoted platen operating arm adapted to be engaged and operated by 55 the cam, a platen connected to and reciprocable by said arm, co-acting means on the cam and arm to raise and release the arm, and a press box with which the platen co-acts.

60 12. In a cotton trumper, a reciprocable platen, a press box for the platen, a rocking arm connected to the platen, a press guide for the platen comprising a plunger connected to the said arm and a cylinder guide for 65 the plunger.

13. The combination with a trumper mechanism comprising a platen and means to reciprocate the platen, of a hydraulic pump operable with the platen and forming a guide therefor. 70

14. The combination with a double press comprising a trumper mechanism, a hydraulic ram, means to operate the trumper mechanism, and means to utilize the power as applied to the operation of the trumper mechanism to generate hydraulic pressure for the operation of said ram. 75

15. In combination, a cotton trumper, a hydraulic baling press, a pump adapted to supply hydraulic pressure for the press, and 80 a common power means for reciprocating the platen and operating the pump. 85

16. In a double box cotton press, a trumper mechanism adapted to co-operate with one box, a hydraulic ram adapted to co-operate with the other box, a cylindrical press column about which the boxes rotate, a plunger reciprocable in the column to form a hydraulic pump, a distribution piping system for the hydraulic pressure, and means 90 to operate the platen mechanism and the pump.

17. The combination with a double box cotton press, of a cylindrical press column, a pump plunger reciprocable in the column, 95 a trumper mechanism movable with and guided by the pump plunger, means to operate the plunger and trumper mechanism, and a hydraulic ram operable by the power generated in said pump. 100

18. The combination with a rotating double press, of top and bottom supports therefor, a hydraulic press column mounted between said supports, a gland in the upper end of the column, a pump plunger reciprocable in the column and adapted to be packed by said gland, a hydraulic ram operable by the hydraulic pressure generated by said pump, an arm pivoted to the upper end of the plunger, a platen operably connected to one end of said arm, a rocking pivotal support for the other end of said arm, and a drive for said arm compressing trip means to lift the arm, and cam means to depress the arm. 110

19. The combination with a press box and its platen, of a vertically rocking arm for operating the platen, means to operate the arm comprising trip means to lift the arm, a power cam to depress the arm, a pawl and ratchet drive for the cam, and an adjustable stop on the arm adapted in its raised position to disengage the pawls. 120

20. The combination with a press box and its platen, of a vertically movable rocking arm for the platen, continuously operating pawls, a ratchet wheel driven by said pawls, a cam and rollers rotatable with the ratchet wheel, a roller on said arm adapted to be engaged and depressed by the cam to force 125 130

the platen downwardly, a trip on said arm adapted to be engaged by the revolving roller to raise and release said arm, a pawl on said arm adapted to engage the ratchet wheel when the arm is raised, and a stop on said arm movable into position to disengage the driven pawls from the ratchet wheel before

said revolving roller releases the trip, substantially as described.

In testimony whereof I affix my signature. 10

JAMES M. PEERSON.
